W. H. ZAHN.

Machine for Making Plated Twist and Cord.

No. 12,845.

Patented May 8, 1855.

UNITED STATES PATENT OFFICE.

WILLIAM H. ZAHN, OF NEW YORK, N. Y., ASSIGNOR TO F. REUTER.

PLAITING AND TWISTING CORD.

Specification of Letters Patent No. 12,845, dated May 8, 1855.

To all whom it may concern:

Be it known that I, WILLIAM H. ZAHN, of the city, county, and State of New York, have invented a new and useful Improvement 5 in Machinery for Making Covered or Plaited Twist and Cord; and I do hereby declare that the following is a full, clear, and exact description of the same, reference being had to the accompanying drawings, 10 forming part of this specification, in which—

Figure 1 is an elevation of a machine constructed according to my invention, and Fig. 2 a vertical section of some parts of the 15 same.

Similar letters of reference indicate corresponding parts in both figures.

This invention consists in certain means whereby cotton or hemp may be covered, or 20 as it is technically termed, "plaited," with silk, or worsted; or any fibrous material be covered or plaited with the same, or a different material, and if desired afterward laid to make cord, at a single operation.

25 To enable those skilled in the art to make and use my invention, I will proceed to describe its construction and operation.

A, A, A, is a stationary framing, in the center of the bottom of which is a journal 30 box or bearing, *r*, for the central hollow journal, or pivot, *b*, of a horizontal or circular table B, which may rotate upon its axis if desired, or be brought to a stationary condition, by inserting a pin, *d*, through 35 one side of the framing, A, A, A, and into a hole in its periphery as is shown in Fig. 1. The hollow journal or pivot, *b*, receives within it the lower part of the vertical, central spindle, C, of a reel shaped flier 40 frame, D, E, F, G, which fits easily within it so that the flier frame may rotate while the table is stationary or the table may rotate while the flier frame is stationary, or the table and flier frame rotate in opposite 45 directions as may be desired. The lower head of the flier frame is composed of two parts, in order to form upper and lower bearings for the spindles (*e*, *e*), see Fig. 2, of the fliers, H, H, see Fig. 1, of which 50 there are supposed to be four, but may be a greater or less number. Each of these spindles carries a spur wheel, *y*, which gears with a circular rack *f*, *f*, on the table, B; the said rack being composed of a series of 55 upright studs, secured in the table.

Each flier carries two bobbins, a larger one, I, carrying the cotton or hempen warp to form the interior of the twist or cord,

having its axle, *g*, supported in the sides of the flier, and a smaller one, J, parallel 60 with, I, carrying the silk or worsted for the plaiting or covering having its axle, *i*, secured at one end in an arm, *h*, attached to one side of the flier.

The bobbin, I, has a drag produced upon 65 one of its heads by a small roller, *j*, carried by a spring, *k*, attached to the lower part of the flier; and the bobbin, J, has a drag produced in a similar manner by a roller, *l*, carried by a spring, *m*.

Above each bobbin and flier, there is a tube, *n*, fitted to turn freely in the upper head, D, of the flier frame, and standing in line with the axis of the flier. This tube, *n*, is best shown at the left hand of Fig. 1, 70 where the head, D, is exhibited partly in section to expose it. To the lower end of this tube below the head, D, there is attached a rod, *o*, entering a loop, *p*, at the top of one side of the flier, and also a light 75 frame, *q*, carrying two rollers, *a*, *a'*, which may be considered in the same light as the nippers of ordinary cordage machines, but has the rollers so arranged that a line intersecting both their axes, is oblique to the axis 80 of the flier, instead of in line, like when rollers are employed as nippers in those machines.

Above the head, D, for each bobbin, there is a roller, *s*, whose axle turns in bearings in 90 two standards, *t*, *t*. This roller carries a wheel, *u*, having teeth on one side gearing with an endless screw, at the top of the tube, *n*, and near the tube, *n*, there is a standard, *v*, carrying a roller, *x*. In the center of the 95 top of the frame A, A, A, there is a tube, *w*.

The warps which are represented in gray color, in Fig. 1, may consist each of a sufficient number of threads or rovings, or of a single thread or roving of proper size. 100 Each passes upward from its bobbin over its respective roller *a'*, thence downward, between the rollers, *a*, *a'*, and under the roller, *a*, where it receives the covering and from whence it ascends in line with the axis of 105 the flier through the tube, *n*, and if a laid cord is to be made, it passes over the roller, *x*, then downward, under the rollers, *s*, and upward toward the tube, *w*, below which the several covered strands are laid together.

The covering which is represented in blue color, consists of a number of filaments arranged together so as to lay parallel, and form a flat sliver or ribbon. It passes from 115 the bobbin to meet the warp just on the un-

der side of the roller *a*, and passes between the warp and the bobbin.

In making laid cord composed of covered strands, the table, *B*, is usually made stationary by inserting the pin, *d*, as before described, and rotary motion is communicated to the spindle, *C*, of the flier frame, through a crank, *L*, pulley, or their equivalent, secured to it below the framing. The 10 flier frame being fast on its spindle rotates with it, and the wheels, *y*, of the fliers, by revolving in gear with the stationary rack, *f*, receive rotary motion on their own axes, and cause the fliers, *H*, to rotate. The tubes, 15 *n*, and the roller frames, *q*, are caused to rotate with the fliers, by the connection with the rods, *o*, and the endless screw, *z*, at the top of the tubes gives motion to the rollers, *s*, which draw off the warps from their bobbins.

The rotary motion of the fliers, gives a slight twist to the warps as they are unwound from their bobbins, by the rollers, *s*, and at the same time causes the covering or 25 plaiting sliver or ribbon to be wound around them. Both the warp and the covering are kept at a proper degree of tightness during the operation by the drag of the rollers, *i*, and *l*, on their bobbins. In order to regulate 30 this drag it may be necessary to apply screws to the springs, *k*, and, *l*, as shown at 6, applied to, *k*. The winding on of the covering or plaiting takes place where it first meets the warp, and as it takes place 35 always at the same point, must be uniform.

The covering is laid smooth by passing between the warp and the roller, *a*, as the winding is performed. The rotary motion of the flier frame lays and twists the several 40 covered strands together and forms the cord in substantially the same manner as common cordage is formed in machines heretofore employed for that purpose.

The cord as it is made is supposed to be 45 wound on a reel whose operation is so controlled as to keep it always drawn tight. The size of the rollers, *s*, will have to be varied to suit different sizes of twist, as the 50 velocity of their peripheries should always be just sufficient to take up the "twist" as it is termed as fast as it is covered. A larger warp will require a larger roller, and vice versa.

If it is only required to make plaited twist 55 such as is used for tassels, fringes, &c., the several warps instead of being laid together after they are covered should be conducted to separate reels, as each in itself constitutes what is known as plaited twist. In that 60 case, however, the flier frame should be made stationary by removing the pin *d*, from the table, *B*, where it is shown in the drawing and passing it through the framing at a higher point where it will enter a hole *j*, in 65 the part *F*, of the flier frame. The crank *L*,

or its equivalent must then be secured to the 70 pivot, *b*, of the table instead of to the spindle *C*, as in the previously described operation. The flier frame now being stationary the revolution of the table *B*, will cause the 75 rack, *f*, to give rotary motion to the fliers severally upon their own axes. In order to attach the crank, *L*, to the spindle, *C*, and detach it from the pivot, *b*, or vice versa as 80 may be desired, I fit the lower part of its hub or eye to the former, and the upper part 85 to the latter, and furnish it with two binding screws, 8 and 9, one opposite the former, and the other opposite the latter, and screw up one and unscrew the other of said screws as may be desired.

For making very small cord an increased speed may be given to the bobbins and fliers, by bringing into operation a small toothed pinion *M*, see Fig. 1, between the rack, *f*, and a rack, 10, which is above the said rack, 90 *f*, on the part, *F*, of the flier frame, at the same time removing the pin, *d*, altogether from the machine, and securing the crank or its equivalent to the spindle, *C*. The rotary motion of the flier frame, will then, through 95 the pinion *M*, and racks, *f*, and, 10, give motion to the table, *B*, at the same speed as, but in the opposite direction to the flier frame, and by that means, the velocity of the wheels, *y*, *y*, of the fliers, and consequently of the 100 fliers themselves, will be doubled.

In making covered or plaited cord, this machine does at one operation, what by the usual process of manufacture requires five distinct operations; and I have estimated 105 that by it the manufacture can be carried on in less than one-thirtieth ($\frac{1}{30}$) of the space required for the same amount of work, by the means now in use.

The operation will be still further expedited by employing two or more bobbins, *f*, in each flier, to carry the covering material, each of the said bobbins, being arranged and operating like the single one represented and described.

What I claim as my invention and desire to secure by Letters Patent is,

The within described arrangement for driving the fliers, consisting of the circular rack, *f*, gearing with their spur wheels, *y*, *y*, 120 said rack being on a table, *B*, which has a central pivot, through which the spindle of the flier frame passes, whereby the fliers are set in operation whether the flier frame, or the table revolves, and are enabled to receive 125 merely a rotary movement on their own axes for making twist, or such rotary movement combined with a revolution around a common axes for making cord, as herein fully set forth.

WILLIAM H. ZAHN.
